BAILER

Filed July 14, 1936

UNITED STATES PATENT OFFICE

2,139,075

BAILER

Paul G. Gates, Long Beach, Calif.

Application July 14, 1936, Serial No. 90,520

16 Claims. (Cl. 166—19)

This invention relates to improvements in bailers and similar devices and may be considered as an improvement over the construction disclosed in my prior Patent No. 2,000,750, issued

5 May 7, 1935, and as an improvement over the construction disclosed in my co-pending application Serial No. 39,131, filed September 4, 1935.

An object of the present invention is to provide a superior "explosion" type bailer and particularly to provide an improved form of valve construction which establishes communication between the lower or entrapping chamber and the top of the bailer when the bailer is landed. The improved form of valve construction is intended 15 to be of very simple yet durable manufacture and of very easy operation. When closed it forms or provides seating surfaces arranged above and below the inlet ports or ingress passages of the valve.

20 Another object of the invention is to provide an improved "explosion" type bailer consisting of means forming two telescopically connected chambers with the upper chamber-forming means equipped with a structure to act as a drag 25 thereon when the bailer is lowered through circulation fluid in a well or other liquid. By this means the upper chamber-forming means tends to have its downward movement retarded during lowering so that during lowering no telescopic movement between the two chambers 30 takes place which would cause premature explosions.

Another object of the invention is to provide a device for cleaning wells of solid material 35 wherein a drill pipe may be lowered having the essentials of the improved bailer construction attached thereto with the top of the drill pipe being open so that when the valve is opened ingress of fluid may take place directly into the 40 drill pipe, thus causing a prolonged period of inrush of fluid and solids into the entrapping chamber. In this connection a more detailed object of the invention is to provide means in the 45 drill pipe for choking back the rate of inflow so that there will not be too great a disturbance of well conditions when the valve is open.

Another object of the invention is to provide a 50 type of fishing tool which is of such design that the tool may be lowered over a fish in a well and even rotated thereabout, after which the "explosion" is caused to take place which is effective to loosen the fish and insure its being caught by the fishing tool, thus enabling its recovery.

With the foregoing and other objects in view, 55 which will be made manifest in the following de-

tailed description, and specifically pointed out in the appended claims, reference is had to the accompanying drawing for an illustrative embodiment of the invention, wherein:

Fig. 1 is a sectional view through the improved 5 bailer embodying the present improvements.

Fig. 2 is an enlarged vertical section illustrating the valve employed, the valve being shown in its closed or seated position.

Fig. 3 is a partial view in vertical section illustrating the invention as having been embodied 10 in a fishing tool.

Referring to the accompanying drawing, wherein similar reference characters designate similar parts throughout, and particularly to Figs. 15 1 and 2, the improved bailer comprises an upper chamber-forming means which may be provided by one or more sections of pipe indicated at 10. The upper end is closed by a suitable closure indicated at 11 which may provide a bail 12 by 20 which the bailer may be lowered into a well through the circulation fluid therein. It will be appreciated, however, that the improved tool is not necessarily restricted in its use to bailing wells but may be used under any analogous conditions, such as for example, obtaining test samples from ocean bottoms.

The bottom of the upper chamber, indicated at 13, is formed by a tubular member 14 into which is screwed a hollow stem 15. The hollow 30 stem 15 is provided at its lower end with an upwardly tapering head 16. The bore 17 through the stem has its lower end normally closed by a ball check valve 18 urged into uppermost and closed position by a spring 19 seated within a 35 plug 20. When the ball check valve 18 is opened, egress from bore 17 is afforded thereby through laterally extending ports 21. The tapered head 16 forms or provides upper and lower seating surfaces 22 and 23 arranged above and below 40 the laterally directed ports 24. In other words, the ports 24 which provide for ingress to bore 17 terminate intermediate the top and bottom of the tapered seating surface of head 16. This head forms a type of valve adapted to seat upon 45 the tapered interior seating surface 25 of a tubular member 26. Packing 27, which is compressed by a gland or nut 28 around stem 15, serves to prevent leakage between stem 15 and tubular member 26. The tubular member 14 50 has a coned bottom 29 and upwardly and outwardly extending passages 30. The tubular member 26 forms a part of a lower chamber defining means, the balance of which is formed by one or more sections of pipe 31, to which is con- 55

nected a bailer bottom 32 having ports 33 which can be opened or closed by means of a sleeve 34 having similar ports that can be moved into or out of registration with ports 33 upon rotation of the sleeve. The sleeve is retained on the bailer bottom in such a manner as to be rotatable by means of a series of balls 35. Races for the balls are formed of the interior of the sleeve and on the exterior of the bailer bottom. The balls 10 are inserted through a small aperture, not shown, which is formed in the sleeve and which is subsequently plugged up to prevent the escape of the balls. The body of the bailer bottom has a vertical central passage 36 formed therein which 15 is normally closed by a downwardly closing entrapping valve 37.

The operation and advantages of the improved bailer are as follows:

When the bailer is lowered into a well the lower 20 chamber-forming means assumes the lowermost telescoping position so as to be suspended by stem 15 with the seating surfaces on head 16 and tubular member 26 in seating engagement. In this position, as shown in Fig. 2, the entrances to the 25 ports 24 are closed and are effectively sealed by virtue of the seating surfaces arranged above and below ports 24. With this valve construction closed air in the upper chamber is confined therein at approximately atmospheric pressure. 30 When the bailer lands at the bottom of the well so that the lower chamber-forming means has its downward movement arrested and therefore moves upwardly with relation to stem 15 and the upper chamber-forming means, head 16 is unseated, with the result that the external or hydrostatic pressure of the liquid into which the bailer is lowered causes the liquid to suddenly enter the bailer bottom past the entrapping valve and into the upper chamber through ports 35 24. The air in the upper chamber which prevents the opening of the valve when at approximately atmospheric pressure compresses highly, allowing this inrush to take place. The sudden inrush of the liquid into the bailer causes debris and other matter to be effectively sucked into the 40 lower entrapping chamber past the entrapping valve and thus become entrapped therein. The bailer may then be withdrawn from the well and upon lifting the bailer the valve provided by head 45 16 again closes. When it has been recovered, upon rotating sleeve 34 to align its ports with ports 33, the contents of the entrapping chamber 50 may be discharged. Valve 18 permits the upper chamber to be emptied thereon without requiring 55 the bailer to be set down on the derrick floor. In other words, while the bailer remains suspended, sleeve 34 may be rotated to open the lower chamber on which an emptying or reduction of pressure in the upper chamber takes place 60 by the escape of pressure past check valve 18.

The purpose of passages 30 is to prevent the upper chamber from dropping with respect to the lower chamber while the bailer is being lowered into a well. The coned bottom surface 29 and 65 passages 30 enable the fluid through which the bailer is being lowered to pass through these passages and the friction developed in so doing acts somewhat as a drag on the upper chamber with the result that the upper chamber has its 70 downward movement retarded. It will therefore not telescope relatively to the lower chamber during the lowering nor cause the bailer to be prematurely set off before it is actually landed.

On Fig. 3 I have illustrated the invention as

having been incorporated in a type of fishing tool. In the preferred form of construction 50 designates the drill pipe by which the construction is lowered into the well. Incorporated in the drill pipe at a suitable distance above the tool there is a balance sub 51 through which is formed a relatively small opening, such as for example, $\frac{1}{2}$ or $\frac{3}{4}$ inch in diameter. This sub may be located in the drill pipe as much as a thousand feet or more above the tool proper. The bottom of the drill pipe is toothed as indicated at 52, the teeth preferably having flat points. The hollow stem 53 corresponds in its construction to stem 15 and its upper end is threaded into the bottom of the drill pipe. Tubular member 54 15 corresponds to tubular member 26 and has a packing 55 compressed by nut 56 around stem 53. The top of tubular member 54 is toothed as at 57 to mesh with teeth 52. A string of drill pipe 58 is attached to tubular member 54 and this string may be of any suitable or preferred length. The top of drill pipe 50 is open so that prior to the opening of the valve afforded by the head on the hollow stem 53 the pressure within the drill pipe above the valve may be substantially atmospheric pressure. Incorporated in the lower string of drill pipe 58 there may be any conventional form of fishing tool and I have illustrated, for example, inwardly extending springs 59 adapted to be caused to engage beneath the 30 collar or tool joint on a lost string of drill pipe. In this form of construction the device is lowered into the well by drill pipe 50 and the drill pipe and tubular member are held spaced from each other by the insertion of a small wooden 35 wedge, not shown, between teeth 52 and 57. The string of drill pipe 58 may be lowered over a lost string or fish and rotated, if desired.

In rotation if any resistance is encountered the wooden wedge inserted between teeth 52 and 57 40 is ground up or mashed up until the teeth engage. This enables the locking of tubular member 54 with drill pipe 50. Also, when the teeth mesh the downward movement of drill pipe 50 with respect to tubular member 54 opens the 45 valve provided by the tapered head on stem 53, causing the fluid in the well around the fish to rush up into the drill pipe 58 through the valve and into drill pipe 50. Drill pipe 50 being dry and having its internal pressure substantially atmospheric allows a prolonged rush of fluid and solids 50 into the fishing tool. This will effectively free the fish so that it may be recovered.

It will be understood that the bottom stem 53 is equipped with a check valve corresponding to check valve 18 and lateral passages indicated at 60 which may correspond to passages 21. This check valve in this form of construction, as well as in the construction illustrated in Figs. 1 and 2, may serve to partially release the pressure 60 entrapped above the valve while at the bottom of the well when the construction is withdrawn. In the form shown in Fig. 3, as the construction is withdrawn from the well pressure inside of the drill pipe, when it becomes in 65 excess of the external hydrostatic pressure, may be partially equalized by means of this valve. As an additional means for bleeding the drill pipe during withdrawal, or as an alternative form of construction drill pipe 50 may be equipped 70 with an outwardly opening check valve 61. If desired, the lower drill pipe section 58 may be equipped with a similar outwardly opening check valve 62. The latter check valve is designed to partially equalize or release pressure during with-

drawal and may come into important use in the event that sand settles around the top of the fish supported within springs 59 closing the bottom of drill pipe 58 in such a manner as to entrap the high pressure at the bottom of the well 5 therein.

The purpose of the blank sub with the small aperture therein is to allow the air in drill pipe 50 to flow quite freely therethrough but when 10 the liquid or mud in the well encounters the sub continued upward flow is materially retarded. In this way by choking back upward flow through the drill pipe, which is prolonged, the well conditions will not be so suddenly and materially 15 disturbed as to cause cave-ins when the valve is open; also the danger of blowouts due to the sudden surge of fluid into the drill pipe will be reduced.

From the above described constructions it will 20 be appreciated that the improved bailer is of very simple design and manufacture and because of its simplicity it is quite durable, having a smooth and highly efficient operation.

Various changes may be made in the details of 25 construction without departing from the spirit or scope of the invention as defined by the appended claims.

I claim:

1. A device of the character described, comprising means providing an upper chamber adapted to be lowered into fluid in a well or other liquid and adapted to confine air or a compressible fluid at approximately atmospheric pressure, said upper chamber-forming means 30 having a downwardly extending hollow stem provided with a tapered head, a lower chamber-forming means telescopically mounted upon said stem carrying means adapted to seat or seal upon said head, said stem and head having 35 passages therethrough terminating on the sides of the head between the top and bottom of the tapered surface thereof whereby seating or sealing surfaces are provided above and below the entrances to the passages.

45 2. A device of the character described, comprising means providing an upper chamber adapted to be lowered into fluid in a well or other liquid and adapted to confine air or a compressible fluid at approximately atmospheric pressure, a stem secured to the upper chamber-forming means having a head, means providing 50 a lower chamber telescopically mounted upon said stem and presenting seating surfaces adapted to seat upon said head, there being inlet ports formed 55 in the head terminating upon tapered sides thereof and adapted to be closed by said seating surfaces.

3. A device of the character described, comprising means providing an upper chamber 60 adapted to be lowered into fluid in a well or other liquid and adapted to confine air or a compressible fluid at approximately atmospheric pressure, means providing a lower chamber telescopically connected to the upper chamber-forming means, means providing a valve adapted to 65 be opened by upward movement of the lower chamber-forming means relative to the upper chamber-forming means, said upper chamber-forming means having passages through its walls 70 whereby fluid on passing therethrough when the device is lowered may by the friction developed retard downward movement of the upper chamber-forming means.

4. A device of the character described, comprising means providing an upper chamber, a

headed stem connected to the upper chamber-forming means, means providing a lower chamber telescopically mounted upon said stem, there being passages through the stem adapted to be closed when the lower chamber-forming means 5 is in its lowermost position with respect to the upper chamber-forming means, and means for locking the upper and lower chamber-forming means against relative rotation when the upper chamber-forming means is in its lowermost position and ingress is afforded to the upper chamber-forming means.

5. A device of the character described, comprising a string of drill pipe having an open top, a stem secured to the bottom of the string of drill 15 pipe, a head on the stem, a lower tubular member telescopically mounted upon the stem above the head, there being passages through the stem adapted to be closed by the tubular member when the tubular member is in its lowermost position, 20 and teeth on the drill pipe and tubular member adapted to engage to lock the tubular member against rotation relatively to the drill pipe.

6. A device of the character described, comprising a string of drill pipe having an open top, 25 a stem secured to the bottom of the string of drill pipe, a head on the stem, a lower tubular member telescopically mounted upon the stem above the head, there being passages through the stem adapted to be closed by the tubular member 30 when the tubular member is in its lowermost position, and teeth on the drill pipe and tubular member adapted to engage to lock the tubular member against rotation relatively to the drill pipe, and means in the drill pipe above the stem 35 forming a restricted passage for retarding upward flow through the drill pipe when passages in the stem are open.

7. A device of the character described, comprising means forming an upper chamber, means forming a lower chamber telescopically connected thereto, a valve adapted to be opened upon relative telescopic movement of the lower chamber-forming means, and means providing a bleeder 40 valve in the lower chamber-forming means below 45 said valve.

8. In a bailer, means defining an upper air chamber having a hollow stem extending downwardly therefrom, a lower entrapping chamber telescopically mounted upon said stem, a tapered 50 head on the bottom of the stem, there being a complementary tapered seating surface on the entrapping chamber forming means engageable with said head, there being one or more laterally directed ports in the head terminating opposite 55 said seating surface when the head is in engagement therewith.

9. A valve for bailers and the like comprising a hollow stem adapted to form a part of an upper air chamber, a tubular member telescopically 60 mounted thereon adapted to form a part of a lower chamber, there being a tapered head on the stem engageable with a tapered seat on the bottom of the tubular part, there being one or more entrances or ports in the head terminating 65 on its tapered surface between the top and bottom thereof so that when the head is engaging the seat said ports will be disposed opposite said seat between the top and bottom thereof whereby seals are formed above and below said ports. 70

10. A valve for bailers and the like, comprising a hollow stem having an upward taper near its bottom, there being one or more ports formed in the stem communicating with the hollow interior thereof and terminating upon said taper, a sleeve 75

slidable upon said stem presenting a seating surface complementary to said taper.

11. In a fishing tool, means defining an upper air chamber having a hollow stem extending

5 downwardly therefrom, a lower entrapping chamber telescopically mounted upon said stem, a tapered head on the bottom of the stem, there being a complementary tapered seating surface on the entrapping chamber-forming means engageable with said head, there being one or more laterally directed ports in the head terminating opposite said seating surface when the head is in engagement therewith.

12. A valve for fishing tools and the like comprising a hollow stem adapted to form a part of

15 an upper air chamber, a tubular member telescopically mounted thereon adapted to form a part of a lower chamber, there being a tapered head on the stem engageable with a tapered seat 20 on the tubular part, there being one or more entrances or ports in the head terminating on its tapered surface between the top and bottom thereof so that when the head is engaging the seat said ports will be disposed opposite said seat 25 between the top and bottom thereof whereby seals are formed above and below said ports.

13. In a bailer or fishing tool, means defining an upper air chamber having a hollow stem extending

30 downwardly therefrom, a lower entrapping chamber telescopically mounted upon said stem, a tapered head on the bottom of the stem, there being a complementary tapered seating surface on the entrapping chamber-forming means engageable with said head, there being one or more laterally directed ports in the head terminating opposite said seating surface when the head is in engagement therewith.

14. A valve for bailers, fishing tools, and the like comprising a hollow stem adapted to form a part of an upper air chamber, a tubular member telescopically mounted thereon adapted to form a part of a lower chamber, there being a tapered 5 head on the stem engageable with a tapered seat on the bottom of the tubular part, there being one or more entrances or ports in the head terminating on its tapered surface between the top and bottom thereof so that when the head is 10 engaging the seat said ports will be disposed opposite said seat between the top and bottom thereof whereby seals are formed above and below said ports.

15. A valve for suction bailers, fishing tools, 15 and the like, having a hollow stem the exterior of which is upwardly and inwardly tapered, there being one or more lateral ports in the stem communicating with the hollow interior thereof and terminating on said taper between the top 20 and bottom thereof.

16. In a device of the character described, a hollow upper member for preserving reduced pressure, a hollow stem extending downwardly therefrom, means defining a lower chamber telescopically mounted thereon, a head on the stem for maintaining the lower chamber-forming means thereon, there being provision made for opening the upper member to the lower chamber through the stem when the lower chamber-forming means is telescoped upwardly on the stem, and means including interengageable teeth formed on the upper member and the lower chamber-forming means for preventing the lower chamber-forming means from telescoping upwardly upon the stem until desired.

PAUL G. GATES.
